(45) **Date of Patent:** **** Oct. 29, 2019**

(54) **WIRELESS EARPHONES**

- (71) Applicant: **Samsung Electronics Co., Ltd.**, Suwon-si (KR)
- (72) Inventors: **Rhys Bonahoom**, San Mateo, CA (US); **Seounghyun Son**, San Francisco, CA (US)
- (73) Assignee: **Samsung Electronics Co., Ltd.**, Suwon-si (KR)
- (**) Term: **15 Years**
- (21) Appl. No.: **29/614,387**
- (22) Filed: **Aug. 18, 2017**
- (51) LOC (12) Cl. **14-01**
- (52) U.S. Cl. **D14/223**

CLAIM

We claim the ornamental design for wireless earphones, as shown and described.

DESCRIPTION

FIG. 1 is a front perspective view of a first embodiment of wireless earphones, showing our new design; FIG. 2 is a front view thereof; FIG. 3 is a rear view thereof; FIG. 4 is a left-side view thereof; FIG. 5 is a right-side view thereof; FIG. 6 is a top view thereof; FIG. 7 is a bottom view thereof; FIG. 8 is a rear perspective view thereof; FIG. 9 is a front perspective view of a second embodiment of wireless earphones, showing our new design; FIG. 10 is a front view thereof; FIG. 11 is a rear view thereof; FIG. 12 is a left-side view thereof; FIG. 13 is a right-side view thereof; FIG. 14 is a top view thereof; FIG. 15 is a bottom view thereof; and, FIG. 16 is a rear perspective view thereof.

The broken lines immediately adjacent the shaded areas represent the bounds of the claimed design while all other broken lines are directed to environment and are for illustrative purposes only; the broken lines form no part of the claimed design.

1 Claim, 10 Drawing Sheets
